CLAIM

The ornamental design for a camping fan, as shown and described.

DESCRIPTION

FIG. 1 is a front perspective view of a camping fan, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof; and,

FIG. 9 is a front perspective view of the camping fan of FIG. 1, shown in another position.

The broken lines in the drawings illustrate the portions of the camping fan, which form no part of the claimed design.
